Des. 215,678
Patented Oct. 21, 1969

215,678

SURGICAL DRILL

Robert M. Hall, % Hall, Inc., Surgical Systems, P.O. Box
4307, Santa Barbara, Calif. 93103

Continuation-in-part of design application Ser. No.
6,869, Apr. 27, 1967. This application Jan. 6, 1969,
Ser. No. 15,221

Term of patent 14 years

Int. Cl. D24—03

U.S. Cl. D83—12

Fig. 1

Fig. 2

Fig. 3

Fig. 5

Fig. 4

Fig. 6

Fig. 7

FIG. 1 is a side elevation view of the surgical drill;
 FIG. 2 is a top plan view of the surgical drill;
 FIG. 3 is a bottom plan view of the surgical drill;
 FIG. 4 is a front end view of the surgical drill;
 FIG. 5 is a rear end view of the surgical drill;
 FIG. 6 is a side elevation view of the surgical drill with the control lever removed; and

FIG. 7 is a plan view of the surgical drill with the control lever removed.

This application is a continuation-in-part of design patent application Ser. No. D-6869, filed Apr. 27, 1967 and now abandoned.

I claim:
 The ornamental design for a surgical drill, as shown and described.
